UNITED STATES PATENT OFFICE.

WILLIAM H. PRINZ, OF CHICAGO, ILLINOIS.

APPARATUS FOR DRYING MALT.

937,011.

Specification of Letters Patent.

Patented Oct. 12, 1909.

Application filed September 8, 1903. Serial No. 172,269.

To all whom it may concern:

Be it known that I, WILLIAM H. PRINZ, a citizen of the United States, residing at Chicago, in the county of Cook and State of Illinois, have invented certain new and useful Improvements in Apparatus for Drying Malt, of which the following is a specification, reference being had to the accompanying drawings.

10 My invention relates to apparatus for drying malt, and has for its object to provide improved apparatus for that purpose which will overcome the principal objections incident to the use of kilns of the common type, 15 in which hot air for drying purposes is passed through the malt on floors arranged one above another, so that the air passes successively through the malt on the different floors, carrying the moisture taken up from 20 one to the next,—the result being that when the air reaches the malt on the last floor it is frequently surcharged with moisture, and consequently is ineffective for drying purposes.

25 By my invention I provide for treating the malt, in its different stages of drying, at all times with fresh air which may be heated to any desired temperature. I also provide means whereby the air used in the finishing 30 stage of the process may be heated to a higher temperature than that used for withering.

My improved drying-apparatus consists of a plurality of rotatable compartments—such 35 as drums or cylinders—adapted to receive the malt,—certain of said compartments being withering-compartments and certain others finishing-compartments. Suitable means are provided for supplying fresh hot air to the 40 withering compartment or compartments, and for supplying fresh hot air at a higher temperature to the finishing compartment or compartments. Any desired number of withering and finishing compartments may 45 be employed. Suitable mechanism is provided for causing a circulation of air through the different compartments, and also for conducting the malt from the withering to the finishing compartments. The drums may be 50 rotated by any suitable mechanism.

In the accompanying drawings,—Figure 1 is a longitudinal vertical section of one of the withering drums; Fig. 2 is a sectional detail of the central part of the casing of the 55 drum which forms the shell of the intermediate compartment; Fig. 3 is a horizontal

section of a building adapted to contain the drying-apparatus, consisting of the withering and finishing drums; Fig. 4 is a horizontal section of the floor above that shown 60 in Fig. 2; and Fig. 5 is a vertical section, illustrating one of the valves for controlling the direction of flow of the air.

The withering and finishing drums are identical in construction, so that a description 65 of the general construction of one of them will suffice for both.

In Fig. 3, A indicates the withering-drum, and B the finishing-drum. C—D indicate compartments in the ends of each drum,— 70 said compartments being separated by an intermediate compartment E, as shown in Fig. 1.

10 indicates the casing or shell of the compartment C: 11 indicates the casing or shell 75 of the compartment D. The casings 10—11 are perforated, as illustrated in Fig. 1. As shown in Fig. 1, said casings are secured at their inner ends to heads 12—13, respectively, which are rigidly connected together 80 by plates 14.

15—16 indicate the heads at the outer ends of the compartments C—D, respectively.

17 indicates the shell or casing of the compartment E, which is composed of a series 85 of overlapping plates 18, the edges of which are fitted between outer and inner annular flanges 19—20, respectively, projecting inwardly from the heads 12—13 near the periphery thereof, as shown in Fig. 1. The 90 edges of the plates 18 fit loosely between said flanges 19—20, so that the heads 12—13 may rotate freely independently of said plates.

21—22 indicate outer and inner tongues at opposite ends of each of the plates 18, as 95 shown in Fig. 2, so that said plates when fitted together form a continuous matched series of overlapping plates. Each of said plates is slightly concavo-convex, to form 100 a circular casing for the intermediate compartment E. The lower portion of said casing engages closely a conduit 23, which projects into the compartment E, fitting closely between the heads 12—13, as shown in Fig. 1, so as to form a substantially air-tight connection. The object of arranging the plates 18 in the manner described is to form substantially air-tight connection between the said plates and the heads 12—13,—since, by 105 the construction described, whether the circulation of the air be effected by pressure or by suction, said plates, being radially mov-

110

able, are held closely in contact with the inner or outer flanges 19—20, as the case may be, by the pressure of the air: consequently the casing of the intermediate compartment automatically adjusts itself accordingly as the pressure of the air may vary, insuring a practically air-tight closure at all times.

5 The casings 10—11 of the compartments C—D rotate in unison independently of the casing 17 of compartment E, since they are connected by the plates 14, as above described. In order that they may rotate freely, they are supported on rollers (not shown) carried by supports 24,—annular rails 25 being provided to rest upon said rollers, substantially as described in my application for patent for malting-apparatus, Serial Number 170,414, filed August 22, 1903 (Case A). The drum is preferably rotated by means of worms 26 engaging worm-wheels 27, as shown in Fig. 1, but any other suitable driving-mechanism may be employed.

28 indicates a manhole in one of the plates 18, which is closed by a suitable cover.

25 29—30 indicate manhole-covers for manholes in the casings 10—11.

31—32 indicate perforated conduits, which extend axially through the compartments C—D,—their ends being secured in the heads 15—12 and 16—13, respectively.

33 indicates a conduit, which is provided at its upper end with a T 34,—the latter connecting with an external extension 35 of the conduit 31. The extension and T 34 are connected by a collar 35, which fits over abutting flanges carried by said members, so as to tightly connect them without interfering with the rotation of the drum. Similarly, a conduit 37 is provided at the opposite end of the drum, and is connected by a T-connection 38 with an extension 39 of the conduit 32,—such connection being formed by means of a collar 40. The conduit 33 communicates with a tunnel 41, and the conduit 37 with a tunnel 42.

43 indicates a tunnel communicating with the conduit 23.

44—45 indicates chutes, placed under the compartments C—D, respectively, in position to register with the manholes therein, for conducting the malt discharged therefrom to elevators 46, shown in Fig. 3. Said elevators are ordinary bucket elevators of the well known type, or, if desired, the malt may be drawn up by suction, or may be transported by any other suitable means.

As best shown in Fig. 3, the tunnels 41—42—43 extend under the floor on which 60 are placed the drums A—B. Between said drums heating-coils 47—48—49 are provided in said tunnels,—said coils being heated by live steam, or other equivalent means, so that the air flowing in said tunnels in the direction indicated by the arrow in Fig. 3 is

further heated after passing the conduits which lead to the compartments in the drum A,—consequently, the air supplied to the compartments in the finishing-drum B is at a higher temperature than that supplied to the withering-drum A.

50—51 indicate conveyers, extending under the malt-compartments of the drum B, for carrying off the finished malt.

52—53—54 indicate flues, leading from the tunnels 41—42—43, respectively, to a fresh-air room F located on an upper floor. Said room contains a steam-coil 55, or other equivalent means, for heating the air therein, and is arranged to extend across the room, so that air passing through said room is compelled to come in contact with said coil.

56 indicates a partition which extends across the room F, separating the room F from a room G which contains an exhaust fan 57.

58 indicates an opening in the partition 56. Where the fan exhausts into the room G, an opening in the partition alone is sufficient. As shown in Fig. 4, the heating coil 55 lies 90 between the opening 58 and the upper ends of the flues 52—53—54, so that air passing from the room G or fan 57 to the flues 52—53—54 necessarily passes through the coil 55,—where it is heated to the desired temperature.

60—61 indicate openings in the wall of the room G, through which external air is admitted thereto. Said openings are provided with valves 62, of the ordinary butterfly type.

63—64 indicate openings in the floor of the room G, which afford communication between said room and the room below in which the drum B is placed. Preferably, the floor below is divided by a partition 65 into two rooms H—I, respectively, containing the drums A—B. The partition 65 is provided with openings 66—67, so that air may pass freely from the room H to the room I.

As shown in Figs. 4 and 5, the openings 63—64 are placed near one of the walls 68 of the building,—said wall being provided with an opening 69 near each of said openings 63—64, as shown in Fig. 5. Butterfly valves 70 are provided for controlling the flow of air through the openings 63—64 and 69, as described in my application filed the 22d day of August, 1903, Serial Number 170,414 (Case A). By means of the valves 70, the air rising from below may be directed outside of the building through the openings 69, or may be directed into the upper room G, as desired.

The operation of the apparatus is as follows: The exhaust fan being set in motion, air is drawn up from below through openings 63—64, passing either into room G or in part outside the building, according as the valve 70 is set. The suction thus created

causes a flow of air through the room F and steam-coil 55 to flues 52—53—54, through which it descends into tunnels 41—42—43. When the conduits 23, 33 and 37 are reached, 5 part of the hot air rises into the different compartments, which are rotated slowly. The air enters each of the malt-compartments C—D at both ends,—being supplied to the conduits 31—32 at their inner ends 10 from intermediate compartment E. By means of said conduits 31—32 the air is uniformly distributed throughout the length of the compartments C—D, passing out through the malt and escaping through the perforations in the casings of the drum into room H. It then passes through openings 66—67 in the partition 65, and finally reaches the openings 63—64,—completing the circuit. That part of the hot air that does not rise 15 through conduits 23, 33, 37 passes on through the tunnels 41—42—43,—being heated by the coils 47—48—49 to a higher temperature before it reaches the corresponding conduits of drum B. Here the same operation is re- 20 peated, except that the air employed is at a higher temperature. When it is desired to re-use all, or a part of, the air, it may be accomplished by setting the valves 70 to close, or partly close, the openings 69. 25

30 When the malt in the drum A has been properly withered, it is discharged through chutes 44—45 which connect with the elevators 46, and by said elevators is carried up and discharged into the drum B through 35 chutes 71—72, shown in Fig. 4. Said chutes are of the usual type.

Owing to the resistance of the malt the pressure in the intermediate compartment E is considerable, but whether such pressure be 40 great or small, there is no material loss of air around the casing-plates 18,—since slight pressure would not suffice for the escape of air between said plates and the inner flanges 20, and greater pressure would force said 45 plates out against the outer flanges 19,—thereby forming substantially air-tight closures at the side edges of said plates, as well as between consecutive plates.

My invention is not restricted to the specific details of the construction described, except in so far as they are particularly claimed, as various modifications may be made. For example, instead of forcing the air into the drums axially thereof and directing it outward through the malt, the 55 operation may be reversed by re-arranging the fan and heating-devices so as to cause the air to circulate in the opposite direction. An apparatus for this purpose is shown in 60 my application for patent, Serial Number 170,415, filed August 22, 1903, (Case B).

That which I claim as my invention and desire to secure by Letters Patent is,—

1. A drying apparatus for malt, comprising a plurality of malt receptacles, means

for supplying heated air, a conduit communicating with said heated-air supplying means and connected separately with a plurality of said malt receptacles, and additional means in said conduit between said receptacles for 70 supplying air through said conduit at different temperatures to different receptacles.

2. A drying apparatus for malt, comprising a plurality of malt receptacles, means for supplying heated air, a conduit communicating with said heated-air supplying means and connected separately with a plurality of said malt receptacles, and additional means in said conduit between said 75 receptacles for supplying air through said 80 conduit at different temperatures to different receptacles.

3. A drying apparatus for malt, comprising a plurality of malt receptacles, means for supplying heated air, a conduit communicating with said heated-air supplying means and connected in succession with a plurality of said malt receptacles, and additional means in said conduit between said 85 receptacles for supplying air through said 90 conduit at different temperatures to different receptacles.

4. A drying-apparatus for malt, comprising a plurality of malt receptacles, a heated air supply, a conduit communicating with 95 said heated air supply and connected separately with a plurality of said malt receptacles, means for varying the temperature of the air supplied to certain of said receptacles, and an elevator for transferring malt 100 from one of said receptacles to the other.

5. A drying-apparatus for malt, comprising a plurality of malt-holding receptacles, air-heating means, an air-tunnel adapted to receive heated air from said heating means 105 communicating with said receptacles, and heating-means in said tunnel between said receptacles, substantially as described.

6. A drying-apparatus for malt, comprising a plurality of receptacles, each having 110 a plurality of malt-holding compartments, means for heating air, a plurality of air-tunnels communicating with the malt-holding compartments in said receptacles, and heating-means in said tunnels between said 115 receptacles.

7. A drying-apparatus for malt, comprising a plurality of malt-holding receptacles, air-heating means, tunnels connecting the ends of each of said receptacles, air-heating 120 means between said receptacles, flues connecting said first mentioned air-heating means with said tunnels, and means for causing the air to flow through said tunnels and malt-holding receptacles, substantially as 125 described.

8. A drum having heads provided with inner and outer flanges forming annular grooves, and overlapping plates loosely fitted in said grooves, substantially as described. 130

9. A drum having heads provided with inner and outer flanges forming annular grooves, and matched plates loosely fitted in said grooves, substantially as described.
10. The combination with a rotary drum, of a non-rotary casing composed of a series of movable plates, and inner and outer flanges adapted to engage the edges of said plates, substantially as described.
11. The combination with a rotary drum, of a non-rotary casing composed of a series of movable plates, inner and outer flanges adapted to engage the edges of said plates, and means for subjecting said plates to air-pressure, substantially as described.
12. A drying apparatus for malt, comprising a plurality of malt-holding receptacles, means for supplying heated air, one or more air conduits communicating with a plurality of said malt-holding receptacles for conducting heated air thereto, and additional means in said air conduits between said receptacles for supplying air through said conduit at different temperatures to different receptacles.
13. A drying apparatus for malt, comprising a plurality of drums having malt-holding compartments, a fresh air room, means therein for heating air, means for supplying air from said room to different drums, additional heating means for varying the temperature of the air supplied to certain of said drums, and means for transferring malt from one of said drums to another.
14. A drying apparatus for malt, comprising a plurality of malt-holding receptacles, a fresh-air room, means for supplying air from said room to said receptacles, means for heating the air supplied to said receptacles, additional heating means for varying the temperature of the air supplied to certain of said receptacles, and means for transferring malt from one of said receptacles to the other.
15. A drying apparatus for malt, comprising a plurality of malt-holding receptacles having externally-perforated shells, a fresh-air room, means for conducting air from said room to said malt-holding receptacles, means for heating the air supplied to said receptacles, and additional heating means between said receptacles for supplying air at different temperatures to different receptacles.
16. A drying apparatus for malt, comprising a plurality of externally-perforated malt-holding receptacles, air-heating means, means for supplying air from said heating means to the different receptacles, and additional heating means between said receptacles for supplying air at different temperatures to different receptacles.
17. A drying apparatus for malt, comprising a plurality of independently-rotatable externally-perforated malt-holding receptacles, air-heating means, means for supplying air from said heating means to said receptacles, and additional heating means between said receptacles for supplying air at different temperatures to different receptacles.
18. A drying apparatus for malt, comprising a plurality of independently-rotatable externally-perforated malt-holding receptacles, a fresh-air room, air-heating means therein, means for conducting air from said room to said receptacles, and additional heating means between said receptacles for supplying air at different temperatures to different receptacles.
